DEVICE FOR INDICATING CUTTING MARKS ON PAPER

Filed May 15, 1930

UNITED STATES PATENT OFFICE

HOWARD BROWN, OF LONGMEADOW, MASSACHUSETTS, ASSIGNOR TO SOUTHWORTH COMPANY, OF MITTINEAGUE, MASSACHUSETTS, A CORPORATION OF MASSACHUSETTS

DEVICE FOR INDICATING CUTTING MARKS ON PAPER

Application filed May 15, 1930. Serial No. 452,795.

Water-marks are commonly placed on paper in the process of manufacture on a Fourdrinier machine and while the paper is in the form of a continuous web or roll.

This invention relates to a device for indicating the lines along which the web of paper should be cut in order to bring the water-marks to uniform positions on the separate sheets into which the web is to be sub-divided.

It is the object of my invention to provide a device for placing a cutting mark or indication on the web during the formation thereof on the Fourdrinier machine.

In the preferred form of my invention, I also provide means for coloring the mark so that it may be more easily detected.

My invention further relates to arrangements and combinations of parts which will be hereinafter described and more particularly pointed out in the appended claims.

A preferred form of the invention is shown in the drawings, in which

Fig. 1 is a plan view of portions of a water-marking mechanism having my invention applied thereto;

Fig. 2 is a front elevation, looking in the direction of the arrow 2 in Fig. 1;

Fig. 3 is a sectional end view, taken along the line 3—3 in Fig. 2;

Fig. 4 is a sectional elevation, taken along the line 4—4 in Fig. 1, and

Fig. 5 is a detail view showing the mark as it appears on the paper.

Referring to the drawings, I have shown a roll 10 to which a series of water-marking plates 11 are secured in the usual manner. The roll 10 is mounted above a guide roll 12 over which the web W of paper passes during the formation thereof. The rolls 10 and 11 are caused to rotate in unison by connecting gears 14, and the roll 12 is positively rotated through power connections, not shown.

The bearings 15 for the water-marking roll 10 are slideable in fixed frame members 16 and are yieldingly pressed downward by levers 17 and weights 18. Downward limits of movement of the bearings 15 and roll 10 are determined by studs 20, threaded into blocks 21 which support the bearings 15.

The lower ends of the studs 20 are received in bushings 22 in the upper face of the bearing blocks 23 for the lower roll 12. The studs 20 may be adjusted by hand wheels 24 through worms 25 and worm gears 26.

The roll 10 is adjusted so that when the web W passes over the guide roll 12 the water-mark plates 11 will press lightly against the damp and partially formed web of paper and will impress the water-mark thereon. The relation of the plates to the web may be adjusted by the hand wheels 24, and the pressure is determined by the weights 18.

The parts thus far described are of a usual commercial construction and in themselves form no part of my present invention, which will now be described.

I provide an additional plate 30 adapted to be secured by screws threaded into selected holes 31 in the surface of the marking roll 10. The plate 30 is provided with a marking projection 32 thereon, preferably in the form of a narrow rib extending axially of the roll 10. The outer surface of the rib 32 is approximately in the same cylindrical surface as the marking surfaces of the plates 11.

As the roll 10 is rotated, the rib 32 comes in contact with the partially formed web W adjacent an edge thereof and forms a mark or depression therein which may be readily seen in the finished paper. This mark is impressed once for each revolution of the roll 10 and is always in predetermined relation to the water-marks impressed by the plates 11. If the web of paper is thereafter cut along the line of the indication 40 (Fig. 5) formed by the rib 32, the water-marks will all appear in a desired location in the subdivided sheets.

The plate 30 may be adjusted on the roll 10 by selecting different holes 31 and also by providing the plate 30 with circumferential slots, so that the rib 32 may be secured in a desired and definite relation to the plates 11.

While the cutting mark thus impressed is effective for the purpose indicated, I preferably provide means for inking or coloring the mark so that it may be more easily de-

tected. For this purpose I provide an inking wheel 50, rotatable in a forked support 51 mounted on a slotted supporting bar 52 and secured in adjusted position by a nut 53. The bar 52 is provided with bushings 54 slideable on studs 55 fixed in the supporting frame 16. An adjusting screw 56 is threaded in the support 52 and the end of the screw 56 is mounted in a bearing member 57 and is held from axial movement by collars 58. A hand wheel 60 is provided for turning the screw 56, by which movement the support 52 and wheel 50 may be adjusted radially toward or from the surface of the roll 10.

Referring to Fig. 4, it will be evident that the wheel 50 is positioned to engage the rib or projection 32 once during each revolution thereof and while the rib is out of contact with the web W. In this way the end of the projection 32 receives a coating of ink or other coloring matter which is thereafter transferred to the web W and forms a mark thereon which is very readily detected. As this mark is applied near the edge of the web, the mark will be cut off in the subdivision of the web into sheets, so that it does not appear in the finished product.

Having described the construction of my improved marking device and the method of operation thereof, it will be evident that I have provided a very simple but effective device for marking a web in exact predetermined relation to the water-marks thereon, so that the web may be easily severed into sheets having the water-marks uniformly located with reference to the edges of the sheets.

Having thus described my invention and the advantages thereof, I do not wish to be limited to the details herein disclosed, otherwise than as set forth in the claims, but what I do claim is:—

1. In a paper-making machine, a water-marking roll having a plurality of water-marking plates secured thereto, a device for making cutting marks mounted on said roll in predetermined relation to said plates, and an inking device mounted adjacent said roll and positioned to engage said marking device at each revolution of said roll.

2. In a paper-making machine, a water-marking roll having a plurality of water-marking plates secured thereto, a device for making cutting marks mounted on said roll in predetermined relation to said plates, an inking wheel, and means to support said inking wheel adjacent said water-marking roll and in the path of movement of said marking device.

3. The combination in a paper-making machine as set forth in claim 2, in which means is provided for adjusting said inking wheel toward and from the water-marking roll.

4. In a paper-making machine, a water-marking roll having a plurality of water-

marking plates secured thereto, an additional plate secured to said roll adjacent one end thereof and in definite relation to said water-marking plates, said additional plate having a marking projection thereon positioned to engage the web once in each revolution of said water-marking roll, and means to apply coloring matter to said marking projection, thereby producing a colored indication.

5. In a paper-making machine, a water-marking roll having a plurality of water-marking plates secured thereto and an additional plate secured to said roll adjacent one end thereof and in definite relation to said water-marking plates, said additional plate having a rib thereon of inverted V section and extending axially of said roll with the top of said projection positioned substantially in the same cylindrical surface as the surfaces of the water-marking plates and thereby engaging the web once in each revolution of said water-marking roll and being effective to produce a surface indication only thereon.

In testimony whereof I have hereunto affixed my signature.

HOWARD BROWN.
